UNITED STATES PATENT OFFICE.

JOSHUA B. HALE, OF PROVIDENCE, RHODE ISLAND, ASSIGNOR, BY MESNE ASSIGNMENTS, TO TEXTILE ENGINEERING COMPANY, A CORPORATION OF RHODE ISLAND.

CARRIER FOR BRAIDING-MACHINES.

1,391,682.

Specification of Letters Patent. Patented Sept. 27, 1921.

Application filed February 2, 1920. Serial No. 355,808.

To all whom it may concern:

Be it known that I, JOSUHUA B. HALE, a citizen of the United States, and resident of the city of Providence, in the county of Providence and State of Rhode Island, have invented certain new and useful Improvements in Carriers for Braiding-Machines, of which the following is a specification.

This invention relates to improvements in 10 yarn carriers for braiding machines; and has for its object to provide such a carrier with an improved rotatable yarn tension and takeup member.

I am aware that it has heretofore been 15 proposed to employ a rotatable yarn-takeup member, but so far as I am aware such devices have never been practically or successfully employed because of vital defects which it is the provience of my invention to 20 overcome, said defects having resulted notably in excessive yarn breakage or undue tension of the yarn and lack of uniformity in action.

A further object of this invention is to 25 provide a latch for controlling the action of the yarn supply, the same being actuated by the rotation of the tension and takeup member to deliver more yarn when required.

With these and other objects in view, the 30 invention consists of certain novel features of construction, as will be more fully described, and particularly pointed out in the appended claims.

In the accompanying drawings:

Fig. 1— is a side elevation of my improved carrier partly in section illustrating its operating mechanism.

Fig. 2— is a front view of the carrier with a portion of the tension standard re- 40 moved to better illustrate the action of the let-off latch.

Fig. 3— is a top view of the carrier with the cop removed.

Fig. 4— is a sectional elevation of the 45 takeup pulley assembly in section.

Fig. 5— is a view of the face of the pulley, showing one arrangement of its actuating coil tension spring.

It is found in practice in the construction 50 of carriers which are designed to run at a very high rate of speed through a serpentine raceway of a braiding machine, that quick operating means should be provided for exerting a practically uniform tension

on the yarn while the carrier is following 55 its zigzag course in which its distance from the braiding point varies; also that the supply shall be released to permit the necessary quantity of yarn to be drawn off as required.

The following is a detailed description of 60 one form of mechanism which enables me to accomplish the desired results:

With reference to the drawings, 10 designates the base portion of the carrier which in this particular case is bifurcated or 65 separated forming upper and lower guiding members connected together by a neck portion 11.

On the upper face of the upper guiding member I have provided a boss 12 to which 70 a tubular cop-supporting member 13 is secured. The upper end of this tubular member is cut away at its sides as at 14 forming arms 15, the inner ends 16 of which are turned inwardly to engage and support 75 a yarn guide eye member 17.

On this central tube is mounted a saucer-shaped disk 18 toothed at 19 on its periphery and to the center of which is secured a tubular member 20 which fits over and is adapted 80 to freely rotate upon the central tube 13. By this construction the usual cop or bobbin 21 mounted on its central paper tube 22, may rest upon and be carried by this saucer-shaped disk, a protuberance 23 being formed 85 in this tube 20 for engaging and locking the paper cop tube thereto so that the cop and its support will turn in unison.

On the upper face of the base portion of the carrier I have secured the lower end 24 90 of the tension standard 25 which is offset from the center of the base sufficiently to provide room for the cop.

In this standard I have rotatably mounted a tension or takeup member which is pref- 95 erably formed in the shape of a pulley 26 having a peripheral groove, said pulley be- ing provided with an inwardly turned hol- low hub 27 extending through and rotatably mounted in the standard, said hollow hub 100 providing a guide eye through which the yarn may be led. On the inner end of this hub I have fixed a disk 29 which serves to hold the pulley in operative position and also on this disk 29 I have mounted an in- wardly extending latch operating pin 30.

In order to provide a bearing of suitable length for the pulley hub I have fixed a

collar member 31 in the standard through which this hub extends and around this collar member I have wound a coil spring 32, one end 33 of which engages the collar and 5 the opposite end 34 is turned inwardly to engage the pulley 26, whereby a yielding tension is exerted on the pulley and on the yarn 35.

A radial slot 36 is formed from the center hole to the periphery of the pulley, 10 through which the yarn is led as it passes through the tubular center to and around the grooved periphery thereof.

In order to control the rotation of the 15 cop-supporting disk 18, I have provided a let-off latch 37 which is pivoted near its lower end at 38 to the standard 25 and is provided with a laterally extending portion 39 which normally rests against the bottom 20 of the standard 25 to serve as a stop to limit the movement of this latch in one direction. From this stop portion the end 40 extends forwardly into engagement with the teeth 19 of the cop-supporting disk 18. The other 25 arm of this latch extends upwardly from its pivoting point, into the path of rotation of the pin 30 on the takeup whereby this pin is caused to bring up against the end of the latch to serve as a stop and limit the rotation 30 of the pulley under action of the spring, but when the pulley is rotated in the opposite direction by drawing off the yarn, the pin 30 follows around and engages the back or opposite side of the latch, causing it to 35 swing to the right on its pivot 38 and raise the end 40 from engagement with the teeth 19 of the disk to permit the latter to rotate with the cop thereon and release more yarn. As soon as a sufficient amount has been 40 drawn from the cop for immediate requirements the tension of the yarn between the pulley and the braiding point, slackens somewhat and the pulley under action of its coil spring begins to rotate in the direction of 45 the arrow, thereby removing the pin 30 from engagement with the back of the latch, which latter under pressure of its spring 41 returns to engage the teeth 19 and arrest further rotation of the bobbin. The surplus 50 yarn or that portion drawn from the supply cop in excess of what is required for immediate use, is wound about the pulley and is subsequently drawn therefrom as the braiding operation proceeds.

55 The tension on the spring 32 may be adjusted by swinging the arm 37 off to the right, as illustrated in dotted lines in Fig. 2, and then rotating the pulley the desired amount, after which the arm is swung back 60 and engaged by the pin 30 and serves as a detent to limit the excessive backward rotation of the pulley.

The radial slot 36 in the face of the pulley 26 is so arranged that when the pin 30 has 65 engaged and moved the latch sufficiently to

draw off more yarn from the cop, then this slot lies in a vertical position or in the direction of the pull of the yarn, so the strain of each first action of drawing the yarn direct from the cop, is reduced to the minimum. 70

By the use of my improved rotary takeup member the yarn is alternately wound about and unwound from the rotatable member, in contrast with the functioning of a reciprocating take-up device, which causes the yarn to take the form of a loop, and to slide forward and backward through a guide eye with the reciprocating action of the takeup element. In my rotary takeup device the 75 80 yarn slides only in the forward direction as it is drawn from the supply through the opening in the pulley bearing, at infrequent intervals.

My rotary takeup member permits more 85 yarn to be wound around its periphery than is required to supply the length necessary for the outward movement of the carrier through its serpentine pathway, thus reducing the number of times it is necessary to 90 draw from the supply. By this construction I also materially reduce the abrading action on the yarn, which is of importance particularly when using such fine and delicate yarns 95 as silk.

My improved takeup and tension device is extremely simple, inexpensive in construction, and effective in its operation and by its use a substantially constant tension is maintained on the yarn during its serpentine 100 travel through the machine and only just the desired quantity of yarn is drawn from the cop each time a fresh draft is made on the supply.

The foregoing description is directed solely 105 toward the construction illustrated, but I desire it to be understood that I reserve the privilege of resorting to all the mechanical changes to which the device is susceptible, the invention being defined and limited only 110 by the terms of the appended claims:

1. claim:

1. A carrier for braiding machines having a rotatable yarn-takeup member provided with a yarn-guiding passageway leading 115 from its center portion to its periphery, a yarn release, and means on said takeup for operating said release when more yarn is required.

2. A carrier for braiding machines having a rotatable yarn-take-up member provided with a centrally and radially disposed yarn passageway leading to its winding surface, a yarn release, and means on said takeup for operating said release when more 120 yarn is required.

3. A carrier for braiding machines having a rotatable yarn-takeup member and provisions for delivering the yarn from the supply to a point substantially radially in 125

the line with the periphery of said takeup member and thence to said periphery, and a yarn release operated by the rotation of said takeup to let off more yarn.

5. 4. A carrier for braiding machines having a rotatable yarn-takeup member provided with a yarn passageway leading from its axis to its winding surface, a yarn release, and means in said takeup for operating said

10 release.

5. A carrier for braiding machines having a rotatable yarn-takeup member provided with a yarn passageway leading from its center portion to its periphery, a yarn

15 release adapted to be operated by said member, and stop-means for said member coacting with said yarn release.

6. A carrier for braiding machines, comprising a base, a rotatable yarn-package support on said base mounted to rotate about a vertically-disposed axis, a standard, and a spring-actuated takeup member rotatably mounted on said standard and having an axial passageway through which the yarn

25 is led from the package to be wound upon the periphery of said member, a yarn release, and means on said takeup for operating said release when more yarn is required.

7. A carrier for braiding machines, having a rotatable yarn-takeup member, a yarn release operated by the rotation of said member, in one direction, a stop on said yarn release and means whereby said stop acts through said release to limit the rotation of

35 said takeup member in the opposite direction.

8. A carrier for braiding machines, having a spring actuated rotatable yarn-takeup member, a yarn-release including a latch 40 operated by the rotation of said member, means on said takeup for engaging said stop to limit the rewinding action of said takeup member.

9. A carrier for braiding machines, comprising a base portion, a vertically-disposed 45 cop support thereon, a tension standard on said base, a spring-operated yarn-tension member rotatably mounted on said standard and about which the yarn is wound, a yarn support, a let off latch controlling the 50 movement of said support, and means whereby the drawing off of a predetermined amount of yarn rotates said member and operates said latch to release said support and permit the delivery of more yarn from the 55 cop.

10. A carrier for braiding machines, comprising a base portion, a cop-support thereon, a tension standard on said base, a rotatable spring-actuated yarn-tension member 60 on said standard around which the yarn is led from the cop, a latch, means whereby a predetermined rotation of said member is caused to operate said latch to release said support and permit the delivery of more 65 yarn from the cop, a stop on said latch to limit the rewinding takeup action of said rotatable member.

11. A carrier for braiding machines, comprising a base portion, a cop-support having 70 a tension standard on said base, a spring-operated rotatable yarn-tension pulley mounted on said standard, said pulley having a hollow yarn guiding center and a radially-disposed yarn guide slot in its face whereby 75 the yarn may be led from the supply through said center and radial guide and about the periphery of the pulley before being drawn off, a latch for controlling the rotation of the cop-support, means whereby a predetermined rotation of the pulley moves said latch to permit the cop to deliver more yarn, 80 said latch also serving as a stop to limit the rewinding or takeup action of said pulley.

In testimony whereof I affix my signature. 85
JOSHUA B. HALE.
